3 Sheets-Sheet 3

UNITED STATES PATENT OFFICE.

HARRY V. ASHBY, OF ERIE, PENNSYLVANIA, ASSIGNOR OF ONE-HALF TO EDWARD B. ASHBY, OF NEW YORK, N. Y.

COLLATING DEVICE.

Application filed July 22, 1924. Serial No. 727,516.

To all whom it may concern:

Be it known that I, HARRY V. ASHBY, a citizen of the United States, residing at Erie, county of Erie, and State of Pennsylvania, have invented certain new and useful Improvements in Collating Devices, of which the following is a specification.

The present invention relates to sheet feeding machines and more particularly to 10 collating machines for associating sheets in groups of two or more.

Heretofore machines of this type have been quite complicated and expensive. The principal aim of the invention is to provide 15 an exceedingly simple, fool-proof machine, and one which rarely if ever fails to feed the sheets properly.

Another aim of the invention is to provide a machine of this type that can be sold 20 at a price low enough so that the small printer can afford to buy it, and yet not sacrifice in any way the efficiency of the machine, for the sake of a low sale price.

Other objects and features of novelty will 25 be apparent from the description taken in connection with the drawings in which:

Fig. 1 is a side view of the machine;

Figs. 2 and 3 are fragmentary side views, 30 showing the combined sheet lifter and conveyor in two different positions;

Fig. 4 is a fragmentary longitudinal vertical section on the line 4—4 of Figure 5;

Fig. 5 is a cross section on the line 5—5 of Figure 4;

Fig. 6 is a detail view, showing a horizontal section through the sheet lifter arm;

Fig. 7 is a sectional elevation illustrating particularly the cam mechanism for operating the sheet lifter and conveyor;

Fig. 8 is an end elevation of the parts shown in Figure 7, certain parts being in section;

Figs. 9 and 10 are vertical sections 45 through the suction and blast nozzles of the combined sheet lifter and conveyor;

Fig. 11 is a detail view of the valve for breaking the suction and the operating means therefor;

Fig. 12 is a fragmentary side view showing a modification of the mechanism for raising and lowering the combined sheet lifter and conveyor;

Fig. 13 is a horizontal section on the line 13—13 of Figure 12.

In the form of the invention illustrated, 55 the frame of the machine comprises two spaced side members each including uprights 10 and upper and lower longitudinal members 11 and 12, respectively. Journaled at each end of the frame is a horizontal tape roller 13, over which pass a number of endless tapes 14, ten of such tapes being shown. Supported by the longitudinal members 12 near the forward end of the frame is an electric motor 15 which 60 drives a countershaft 16 through a silent chain drive 17. A pulley on shaft 16 is connected to a pulley on the shaft of rear roller 13 by a belt 18 for operating the tapes 14.

Secured to the upper horizontal members 11 of the frame are a plurality of longitudinally spaced tables 19 which extend entirely across from one longitudinal member to the other above the upper runs of tapes 75 14 (Figure 11). Each table has secured to the forward edge thereof a plurality of sheet guides 20.

Each of these tables supports a pile of sheets. A sheet from the various piles is 80 simultaneously taken from the top of all of the piles and delivered onto the tapes which discharge the sheets in groups. One of the novel features of the present invention resides in the means for positively separating 85 the top sheet from the pile and depositing it on the tapes. For this purpose a combined sheet feeder and conveyor is employed. This feeder is permitted to fall onto the top of the pile and picks up the top sheet and then the feeder together with the sheet travels to a point where the sheet may be delivered onto the tapes.

For the purpose of causing the feeder to travel horizontally there is secured to each 95 longitudinal member 11 a pair of guides 21, each pair supporting anti-frictionally a reciprocating bar 22 which has a depending arm 23 extending through a slot 24 formed in the adjacent member 11. The ends of arms 23 are connected by links 25 to the upper ends of levers 26 fulcrumed at their lower ends at 27 on the longitudinal members 12 and connected at an intermediate point of each by a cross rod 28. Pivoted to rod 28 centrally thereof is a link 29 (see Figure 7) which has a longitudinal slot 30 through which a cam shaft 31 extends being

mounted in bearings 32 secured to the longitudinal members 12. This shaft has secured thereon adjacent the link 29 an open faced cam 33 which is engaged by a roller 34 on link 29. Shaft 31 is driven from shaft 16 by a silent chain drive consisting of a chain 31' passing over a small sprocket on shaft 16 and over a larger sprocket 35 on shaft 31 (Figure 1). A spring 36 tends to move levers 26 to the right as viewed in Figure 1. Rigidly secured to each bar 22 are a plurality of vertical guides 37, the guides of one of these pairs being directly opposite, or in transverse alignment with, the guides 15 on the other pair. Each transversely aligned pair of guides is connected by a cross rod 38. Mounted for up and down reciprocation in each pair of transversely aligned guides 37 is a sheet lifter 39 secured at each 20 end to a head 40. Journaled on the outer face of each head 40, are two vertically aligned rollers 41 which work in the respective guides 37, whereby the sheet lifters are anti-frictionally guided for up and down or 25 vertical reciprocation. Rigidly secured to each head 40 is a depending arm 42 which has mounted on the outer face thereof just below head 40 a roller 43, the several rollers being adapted to roll on the upper surface 30 of the longitudinal members 11. As clearly shown in Figure 6, the tables 19 have their forward corners cut away and the inner margins of the longitudinal members 11 are also notched at these points, forming apertures 35 through which the rollers 43 are adapted to pass when the sheet lifters approach the limit of their movement towards said tables, thereby permitting said sheet lifters to drop on to the sheet piles carried by the 40 tables for the purpose of picking up the top sheet. For elevating the lifters after they have dropped on to said piles the following mechanism is provided: Journaled in brackets depending from the upper longitudinal 45 members 11 are transverse shafts 44, one for each sheet lifter, which extend between the upper and lower runs of belts 14 under the respective tables 19. Rigidly secured to each shaft 44 adjacent each end thereof is an arm 50 45 which carries at its free end a roller 46 which is adapted to engage a face formed on the lower end of the respective arm 42. Rigid with one of the arms 45 of each shaft 44, is a depending arm 47 and pivoted on shaft 44 adjacent arm 47 is an arm 48 which is adapted to engage a lateral abutment, or flange, 49 on the depending arm 47. The ends of arms 48 are engaged in brackets 50 secured to a longitudinal rod 51 which is 55 mounted for longitudinal reciprocation in guides 52 attached to the inner faces of uprights 10. The rod 51 is reciprocated by means of a lever 53 which has its upper end engaging a bracket 54 on the rod 51 and which is fulcrumed at its lower end on lon-

gitudinal member 12 of the frame. Lever 53 carries at an intermediate point a laterally projecting roller 55 which cooperates with a cam 56 secured to shaft 31. A spring 57 holds lever 53 against cam 56. The sheet lifters 39 are similar to those described in my copending application, Ser. No. 649,964, filed July 6, 1923. Each comprises a longitudinal bar having two interior conduits communicating respectively with blast and suction means and provided with blast and suction nozzles communicating respectively with said conduits. Referring particularly to Figure 5, 10 and 11, the sheet lifter shown comprises an elongated member or bar formed with two interior superposed longitudinal conduits 57 and 58. The upper conduit 57 is connected by flexible hose 59 to a horizontal overhanging pipe 60 which communicates with a vertical pipe 61 projecting from a longitudinal pipe 62 leading to the exhaust of a vacuum pump 63. The lower conduit 58 of each lifter is connected by a flexible hose 64 to the upper end of a vertical pipe 65, the lower end of which is connected to a longitudinal pipe 66 leading to the intake of the vacuum pump 63. Interposed in each vertical pipe 65 is a sleeve valve (see Figure 11) comprising a rotary sleeve 67 provided with a slot 68 which is adapted to register with a slot in pipe 65. The sleeves 67 have lateral arms 67^a which are connected by a rod 69 slidably mounted in guides 70 secured to the longitudinal member 11 of the frame. A spring 71 secured to the rear end of rod 69 and to a pin 71^a on member 11 tends to hold the sleeve valves closed. An inwardly projecting pin 72 on rod 69 is adapted to be engaged by the depending arm 23 of bar 22 when the sheet lifters approach the limit of their movement away from the sheet piles and are in position to deposit the sheets carried thereby on to the continuously moving tapes 14 whereby the valves are opened, breaking the vacuum and permitting the sheets to drop. The lower or suction conduits 58 of the sheet lifters communicate with a number of regularly spaced suction nozzles 73 which all open in the same horizontal plane (Figures 9 and 10). Combined with each of the suction nozzles is a blast nozzle 74 or 75. As will be observed from Figures 9 and 10, the blast nozzles 75 are directed to deliver blasts downwardly on the marginal edges of the sheets at the top of the pile and so operate to force down and away from the top sheet any sheets which may adhere thereto. Nozzles 74 are directed to deliver blasts against the edges of the sheets at the top of the pile and thereby force air between the top sheet and next sheet to hold the top sheet separated from the next sheet. Some of the suction nozzles 73 have associated therewith

blast nozzles of the form designated by 74, while other suction nozzles are associated with blast nozzles of the form designated by 75. The arrangement of the nozzles may be varied as desired, but it is preferable to combine the form of blast nozzle designated by 74 with at least two of the central suction nozzles as well as with some of the outer suction nozzles. In other words, no fixed arrangement of these nozzles is shown or claimed herein, as the arrangement will be varied as conditions require. The nozzles may be equipped with cocks 73^a for cutting out any one or more thereof, as more fully described in my copending application, serial No. 1,575,893. As shown in Figure 5, three of the outer or end nozzles are provided with these cocks 73^a so that if sheets of a width narrower than the entire width of the feeder are being collated, the nozzles that are not necessary for action on the sheet may be shut off. The machine, as described above, is adapted to collate or associate sheets in sets of two, but of course the machine may be equipped with any desired number of sheet tables and associated sheet lifting and conveying devices. Each table holds a pile of sheets, the sheets comprised in a pile being identical, but the sheets in the several piles being different as to the character of the printed or other matter thereon, the function of the machine being to associate the sheets in sets, each of which consists of one sheet from each pile. Let it be assumed that the sheet lifters have deposited their sheets on the tapes 14 and are moving back towards the sheet piles. The shaft 31 is continuously rotating in a clockwise direction, looking at Figure 7. From the shape of the cams 33 and 56, it will be noted that the cam 33 causes the lever 26 to be moved to the limit of its right hand stroke just before the roller 55 rides off the high part of cam 56 and that the cam 33 is so formed that the lever 26 will then dwell while the shaft 31 is rotating through an angle of about 120°. When lever 26 is thus brought to the right hand limit of its stroke, the rollers 43 supporting the sheet lifters drop through the notches at the inner margins of members 11 and the lower ends of arms 42 come into engagement with, and rest on, arms 45 so that the sheet lifters are supported by said arms. The roller 55 thereupon passes from the high to the low part of cam 56, permitting spring 57 to move lever 53, bar 51 and arm 48 to the right, looking at Figures 1 and 7, thereby permitting arms 45 to drop under the weight of the sheet lifters, the rollers 43 passing through the apertures, one of which is shown in Figure 6, and the sheet lifters dropping onto their respective sheet piles. The suction nozzles 73 now rest squarely on the forward edge of the top sheet while the blast nozzles 74 and 75 are directed at the edges of the upper sheets of the pile. The cams 33 and 56 are now in the positions shown by Figure 7. On further rotation of the shaft 31 in clockwise direction, cam 56 causes lever 53, rod 51 and arm 48 to be swung to the left and the arms 45 to be rotated upwardly. The upward rotation of arms 45 raises the sheet lifters from the sheet pile, the suction and blast nozzles functioning in the manner heretofore pointed out to cause the top sheet to be separated from the pile of sheets and adhere to the suction nozzles. When the sheet lifters have thus been lifted by cam 56, the concentric part of cam 33 passes from engagement with roller 34 and the lever 26 is moved rapidly to the left causing the sheet lifters to travel away from the sheet piles and over the continuously moving tapes 14. When the lifters approach the limit of their movement in this direction the depending arm 28 of bar 22 strikes pin 72 on rod 69, causing the sleeve valves 67 to open and break the vacuum of the suction nozzles, thus releasing the sheets and permitting them to fall on the tapes. Attention is called to the fact that air under pressure is supplied to the blast nozzles continuously, so that the blasts delivered by these nozzles when the suction is broken positively assists gravity in releasing the sheets from the suction nozzles. It will be observed from the shape of cam 33 that the sheet lifting and conveying devices will have a short dwell when at the limit of their movement away from the sheet piles thus giving sufficient time to fully release the sheets and let them fall on the continuously moving tapes before the said devices begin their return strokes. After this dwell the shape of the cam is such as to move the devices quickly back to their respective sheet piles. The velocity of the tapes 14 is so timed with reference to the operation of the sheet lifting and conveying devices that all the sheets deposited on the tapes at a single operation of said devices will be moved past the last device in the direction of movement of the upper runs of said tapes before another set of sheets is deposited on said tapes. The sheets are delivered by the tapes into a suitable receptacle 76 at the forward end of the machine. Figures 12 and 13 show a modified construction of the means for lifting and controlling the sheet lifting and conveying devices. Here the rollers 43, which are mounted on downwardly extending arms rigid with the sheet lifter heads 40 operate on pivoted tracks 77. The free ends of these tracks have depending heads 78 adapted to be engaged by rollers 46, which are operated as described above. It will be understood from the above description that when the sheet lifter and conveying devices approach

the limit of their movement towards the sheet piles, the tracks 77 are permitted to swing downwardly about their pivots permitting the sheet lifters to drop on to the sheet piles, and that said tracks are thereafter raised into a horizontal position flush with side member 11 and maintain this position until the sheet lifters again approach the limit of their movement towards the sheet piles. This is effected by the operation of cam 56 and the train of mechanism, previously described, between this cam and arms 45.

Having thus described the invention what is claimed as new and desired to be secured by Letters Patent is:

1. A collating machine including in combination, a frame, a transverse horizontal roller journaled in said frame adjacent each end thereof, endless tapes passing around said rollers, means for rotating one of said rollers, a plurality of longitudinally spaced tables mounted on said frame slightly above the upper runs of said tapes, each adapted to hold a pile of sheets, and a single means associated with each pile of sheets for lifting sheets singly therefrom and depositing them simultaneously on said tapes at longitudinally separated points thereof, the velocity of said tapes being so timed with respect to the operation of said means that all sheets simultaneously deposited on said tapes will be moved past the last said means in the direction of movement of the upper runs of said tapes before a second set of sheets is deposited thereon.

2. A collating machine including in combination, an elongated frame, means moving longitudinally of said frame for conveying sheets to a common point, a plurality of longitudinally spaced tables mounted on said frame slightly above said sheet conveying means, each adapted to hold a pile of sheets, and a single means associated with each pile of sheets for lifting sheets singly therefrom and depositing them simultaneously on said conveying means at longitudinally separated points thereof, the velocity of said sheet conveying means being so timed with respect to said lifting and depositing means that all sheets simultaneously deposited on said conveying means will have moved past the last lifting and depositing means in the direction of movement of the conveying means before a second set of sheets is deposited.

3. A collating machine including in combination, a frame, means moving longitudinally of said frame for conveying sheets to a common point, a plurality of longitudinally spaced tables mounted on said frame slightly above said conveying means, each adapted to hold a pile of sheets, and a suction device associated with each pile of sheets for lifting sheets singly therefrom

and depositing them simultaneously on said conveying means at longitudinally spaced points thereof.

4. A collating machine including in combination, a frame, a transverse horizontal roller journaled in said frame adjacent each end thereof, endless tapes passing around said rollers, means for rotating one of said rollers, a plurality of longitudinally spaced tables mounted on said frame slightly above the upper runs of said tapes, each adapted to hold a pile of sheets, a suction device associated with each pile of sheets, and means for operating said suction devices to cause them to lift sheets singly from their associated piles and convey and simultaneously deposit said sheets onto said tapes at longitudinally spaced points thereof.

5. A collating machine including in combination, a frame, means for supporting a pile of sheets at each of a plurality of positions on said frame, sheet conveying means adapted to convey sheets to a common point, a suction device associated with each pile of sheets, and means for operating said suction devices to cause them to lift sheets singly from their respective piles and convey and simultaneously deposit said sheets on said conveying means, said conveying means operating at such speed that all sheets simultaneously deposited thereon are conveyed to the common point before the next set of sheets is deposited.

6. A collating machine including in combination, a frame, means for supporting a plurality of piles of sheets at longitudinally spaced positions on said frame, a set of endless tapes common to all of said piles, a suction device associated with each pile, and means for operating said suction devices to cause them to lift sheets singly from their respective piles and convey and simultaneously deposit said sheets on said tapes at longitudinally spaced points thereof, said tapes operating at such speed that all sheets simultaneously deposited thereon are conveyed to a common point before the next set of sheets is deposited.

7. A collating machine including in combination, a frame, means for supporting a pile of sheets at each of a plurality of positions on said frame, sheet conveying means adapted to convey sheets to a common point, a sheet lifting and depositing device associated with each pile of sheets each device comprising a plurality of combined suction and blast nozzles, and means for operating said devices to cause them to separate and lift sheets singly from their respective piles and convey and simultaneously deposit said sheets on said conveying means, said operating means including means to break the vacuum in said vacuum nozzles when said devices approach their sheet depositing positions, the blast nozzles continuing to deliver blasts

which positively disengage the sheets from the suction nozzles.

8. In a sheet feeding machine in combination, means to support a pile of sheets, a device to take the sheets singly from said pile comprising a bar having two interior longitudinal channels and having suction and blast nozzles rigid with said bar and in communication with said channels respectively, means to connect the suction and blast channels to the intake and exhaust respectively of an air pump, said suction nozzles opening vertically downward and said blast nozzles opening in front of and below said suction nozzles at different angles to the vertical operating means for said bar to move the nozzles over the forward edge of the pile and then down on the sheet pile, so that the suction nozzles rest on the forward margin of the top sheet while the blast nozzles open close to the edges of the top sheets, said operating means then causing the nozzles to rise and move away from said pile to a distant point, and means to break the suction in said suction nozzles when the sheet approaches said point, the blast nozzles continuing to deliver blasts which positively disengage the sheet from the suction nozzles.

9. In a sheet feeding machine in combination, means to support a pile of sheets, a device to take the sheets from said pile and deliver same to a distant point comprising a plurality of combined suction and blast nozzles, said suction nozzles opening vertically downward and said blast nozzles opening in front of and below said suction nozzles at an angle to the vertical, suction and exhaust means connected to said suction and blast nozzles respectively, means for moving said device downward to bring the suction nozzles into contact with the forward margin of the top sheet and the blast nozzles in proximity to the edges of the upper sheets and for then moving said device upward and horizontally to a distant point, and means for breaking the suction in said suction nozzles when the sheet approaches said point, the blast nozzles continuing to deliver blasts which positively disengage the sheet from the suction nozzle.

10. In a sheet feeding machine in combination, means to support a pile of sheets, a device to take sheets singly from said pile and deliver them to a distant point, said device comprising a plurality of combined suction and blast nozzles, suction and exhaust means connected to said suction and blast nozzles respectively, means to move the device to and from the sheet pile, and means to break the suction in said suction nozzles when approaching the limit of movement away from the sheet pile, the blast nozzles continuing to deliver blasts which positively disengage the sheet from the suction nozzle.

11. In a sheet feeding machine in combina-

tion, means to support a pile of sheets, a device to take sheets singly from said pile and deliver them away from said pile, said device comprising a combined suction and blast nozzle, suction and exhaust means connected to said combined nozzle, means to move the device to and from the sheet pile, and means to break the suction in the suction nozzle when approaching the limit of the movement away from the pile, the blast nozzle continuing to deliver a blast which positively disengages the sheet from the suction nozzle.

12. A collating machine including in combination a frame, a transverse horizontal roller journaled in said frame adjacent each end thereof, endless tapes passing around said rollers, means for rotating one of said rollers, a plurality of longitudinally spaced tables mounted on said frame slightly above the upper runs of said tapes, each adapted to hold a pile of sheets, a guide associated with each table, a sheet lifting device vertically reciprocable in said guide, means to reciprocate said guides towards and from their associated tables, said means causing the guides to dwell when reaching the limits of their movements towards the tables, and means for lowering and raising said devices during said dwell.

13. A collating machine including in combination a frame, a transverse horizontal roller journaled in said frame adjacent each end thereof, endless tapes passing around said rollers, means for rotating one of said rollers, means to support a plurality of piles of sheets at longitudinally spaced points above the upper runs of said tapes, a guide associated with each pile of sheets, a suction sheet lifter mounted for up and down movement in each guide, rollers supporting the lifters on the frame, cam means for reciprocating said guides to and from their respective sheet piles causing substantial dwells at the limits of the movements, movable members adapted to support the sheet lifters when the latter are at the limits of their movements towards the sheet piles, cam means to move said members down and then up to lower and then raise the lifters during the dwell of the guides, and means to break the suction in said lifters when approaching the limit of their movement away from the piles.

14. In a sheet feeding machine in combination, means to support a pile of sheets, a guide, a sheet lifter mounted for up and down movement in said guide, said lifter comprising a combined suction and blast nozzle, suction and blast means, flexible hose connecting said means with said nozzles, cam means for reciprocating said guide to and from the pile causing substantial dwells at the limits of the movement, a movable member adapted to support said lifter when

BEST AVAILABLE COPY

1,575,893

at the limit of its movement towards the sheet pile, cam means to move said member down and then up to lower and raise the lifter during the dwell and means to break the suction when the lifter approaches the limit of its movement away from the pile, the blast means continuing to deliver a blast which positively disengages the sheet.

15. A sheet collating machine including in combination, a plurality of longitudinally spaced pile tables, a series of tapes traveling under said tables, a combined sheet lifter and conveyor for each pile, means to

lower said lifter into contact with the top sheet of the associated pile to pick up a sheet, and then raise said lifters, means to reciprocate said lifters horizontally to carry the sheets to a position over the tapes and then return the lifters, and means to cause the lifters to take the top sheet of each pile when in contact therewith and release the sheets when in said position over the tapes.

In testimony whereof I hereunto affix my signature.

HARRY V. ASHBY.
